not essential to an understanding of the invention being but diagrammatically represented.

Figure 2 is a cross section taken substantially on the indicated line 2—2 of Figure 1.

5 Figure 3 is a fragmentary, detail section, on an enlarged scale, vertically and axially through a fluid outflow assembly illustrated in elevation in Figure 1.

Figure 4 is a cross section, on a further enlarged scale, taken substantially on the indicated line 4—4 of Figure 1.

10 Figure 5 is a vertical section similar to Figure 1 taken substantially axially through a modified embodiment of the invention.

Figure 6 is a fragmentary, detail section taken substantially on the indicated line 6—6 of Figure 5.

Figure 7 is a fragmentary, detail elevation, on a relatively enlarged scale, of an adjustable control means included in the organization according to Figure 5.

Figure 8 is a fragmentary, detail elevation of means 20 adjustably reactive to the control shown in Figure 7.

Figure 9 is a vertical section, similar and on an enlarged scale relative to Figures 1 and 5, taken axially through an alternatively modified embodiment of the invention, an intermediate portion of the view being broken 25 away to conserve space.

Operable to better accomplish the functions of the apparatus disclosed in my application above noted through structures generally analogous to that shown in said application, the instant invention includes a preferably-cylindrical, axially-upright tank 10 of appropriate size and material, closed save as hereinafter specified and formed with a circular opening centrally of its top end closure for the loose accommodation of a tubular, open-

30 end well 11 depending therethrough coaxially and interiorly of the tank. The open upper end of the well 11 projects above the upper end of the tank 10 and is supported by the latter for rotation about its axis in any expedient manner, as by means of an anti-friction bearing 12 operatively between the tank top closure and an annular flange 13 adjacent the upper end of the well above said tank closure, and any suitable power means, typified by an electric motor 14, is arranged in any expedient manner to steadily and uniformly rotate the well 11 about its axis as, for example, through a gear train 15 in driving relation with a gear 16 peripherally of the flange 13.

35 In further analogy with the disclosure of my earlier application, the well 11 carries a continuous spiral flight 17 fixedly outstanding radially and exteriorly of the well to substantially bridge the area between said well and the interior wall of the tank 10 in a pitch, or inclination, productive of elevating effect when the well is rotated in a predetermined direction characteristic of apparatus operation, and the inner cylindrical wall of the tank 10 is expediently vertically ribbed, as at 18, to minimize circulatory effects within said tank deriving from rotation 40 of the well and its associated flight 17.

45 As in my earlier application above noted, feed of material to be treated is led to and through the open upper end of the well 11 in any expedient manner and through any appropriate means, such as a conduit 19 disposed for delivery to and centrally of the upper end of the well, as in Figure 1, a conveyor 20 arranged for similar delivery, as in Figure 9, or a hopper chute 21, as in Figure 5, and the water supply to the tank is had 50 and maintained through a line 22 leading from any suitable source or supply of water through a flow-regulating valve 23 to deliver interiorly and adjacent the upper end of the tank 10 exteriorly of the well 11 therein. As in the case of my earlier disclosure, withdrawal of solution 55 from the apparatus is had at the zone of maximum solution concentration through an out-flow line 24 sealed through the bottom of the tank 10 to upstand in coaxial

As a development from and an improvement in certain respects over the apparatus disclosed in my pending application for United States Patent filed August 1, 1952, Serial No. 302,151, now Patent No. 2,749,258, this invention relates to apparatus for the extraction of sugar content from sugar beet material, and the like, and has as an object to provide a novel and improved means for the continuous leaching of sugar content from such material with expedition and efficiency.

A further object of the invention is to provide a novel and improved diffusing cell, or unit, applicable with efficiency and economy to the continuous processing of sugar beet or analogous material for extraction of the sugar content therefrom.

A further object of the invention is to provide a novel and improved construction and operative correlation of elements constituting a diffusing cell, or unit, for the continuous leaching of sugar content from sugar beet material, or the like.

A further object of the invention is to provide a novel and improved diffusing cell, or unit, for the continuous extraction of sugar content from sugar beet material, or the like, that is promotive in operation of novel circulation of its contents and enhancing of the sugar content recovery accomplished therein.

A further object of the invention is to provide a novel and improved diffusing cell, or unit, for extraction of sugar content from sugar beet material, or the like, that accommodates regulation and control of various factors pertinent to the efficient recovery of sugar content during continuous operation thereof.

A further object of the invention is to provide a novel and improved diffusing cell, or unit, for the continuous recovery of sugar content from sugar beet material, or the like, that is characterized by means inhibitive of congestion within the apparatus which tends to interrupt the efficient operation thereof.

A further object of the invention is to provide an improved diffusing apparatus adapted for continuous operation that is simple and relatively inexpensive of construction and operative installation, that is economical of power required for its operation, that is susceptible of practical development in a wide range of sizes and capacities amenable to operative correlation with conventional auxiliary equipment, that is readily regulable to accommodate variation of the material feed thereto without interruption of continuous operation, that is free from onerous maintenance and servicing requirements, and that is positive and efficient in attainment of the ends for which designed.

With the foregoing and other objects in view, my invention consists in the construction, arrangement, and operative combination of elements as hereinafter set forth, pointed out in my claims, and illustrated by the accompanying drawings, in which—

Figure 1 is a vertical section taken substantially axially through a typical embodiment of the invention as arranged ready for practical use, certain associated elements

relation with and upwardly through a major length of the well 11 to terminate below the liquid level normally obtaining within said well during operation of the apparatus, and such liquid level is regulably determined and controlled by means of an adjustable weir trap 25, expediently of the general type and construction shown in my earlier application, wherethrough flow from the line 24 is received and directed to a delivery line 26 in a manner to apply adjustments of the trap weir for regulation and control of liquid level within the well 11, all in an obvious manner. Feed of material to be treated through the upper end of the well 11, supply of water to the tank 10 adjacent the upper end thereof and exteriorly of the well, withdrawal of solution from an upper zone of the well interior, and rotation of said well for elevating effect characteristic of its spiral flight 17, combine to establish a circulation of the material to be treated downwardly through said well and upwardly through the areas of the tank exterior to said well in opposition to the circulation of water from the supply line 22 and to the intake end of the outflow line 24, and to concentrate the leached material in the upper end of the space within the tank and about the well 11 in position to be removed from the apparatus by means of a sweep 27, or equivalent, carried by and for rotation with the well 11 in a disposition effective to divert the leached material from the upper surface of the tank liquid charge and outwardly of said tank through an inclined launder 28 open to the tank interior just above the upper end of the flight 17.

The general organization represented and hereinabove described as analogous to my earlier disclosure functions as set forth therein to correlate regulable supply of material to be leached with a regulable supply of water for countercurrent circulation of water and material in and as a charge of regulable level in a manner facilitating continuous operation characterized by withdrawal of solution from a zone of maximum solution concentration, and the improvements of the instant invention, hereinafter set forth, are directed to novelties of structure, structural relationships, and operative correlations effective within the general organization above described to enhance the efficiency and to promote the utility of the operations therein accomplished.

A first significant feature distinguishing the instant invention from the disclosure of my earlier application is the provision at the lower end of the tank 10 of a lower end closure for the tank in the form of an annular trough 29 having the general form of a hollow torus bisected by a plane perpendicular to the axis of its generation, which annular trough 29 is conveniently semi-circular in an arc closing between the wall of the tank 10 and the surface of the outflow line 24 in an arrangement wherof the concavity registers and combines with the tank interior, thus to direct the trough convexity outwardly and downwardly of the tank; the concavity of the annular trough 29 closing the lower end of the tank 10 in part underlying the lower end of the well 11 in position to receive material descending through said well and to urge such material radially and outwardly of the tank and into the zone of spiral flight 17 action. To promote desired circulation of the material received within the annular trough 29 and to inhibit compaction of such material within said trough and hence away from the direct influence of the spiral flight 17, blades 30 fixedly depend in angularly spaced relation from the lower end of the well 11 within the said trough and in slightly spaced marginal conformity therewith to each substantially obstruct the trough transversely thereof and preferably radially of the tank 10 in a disposition and relation effective to agitate and dislodge material received within the trough and to circulate and recirculate such material, with enhanced leaching effect, as indicated by the arrows in Figure 1. Thus the conformation of the tank 10 and rotation of the well 11 coact to inhibit any

accumulation of material diverted from its circulatory path within the apparatus and to stimulate the leaching of such material as an incident of its agitation within and repetitious free circulation through the liquid charge.

A further significant feature distinguishing the instant invention is the provision of means for maintaining free intake flow of solution to the receiving end of the outflow line 24 within an upper zone of the well 11. Since the input of material to be leached is had adjacent and past the intake end of the flow line 24 through a rather restricted zone of the well 11, there is a tendency for the material to collect about the intake end of said line, and to compact against any screen protecting said intake end, in a manner undesirably obstructive of outflow through the line 24 and interruptive of material circulation through the apparatus. Operable as an incident of well 11 rotation to maintain the intake end of the line 24 open to free inflow and to inhibit compaction of material in obstruction relation with said intake, a self-cleaning screen is expediently associated with the intake end of the line 24 in a form and construction typified in Figures 1, 3, and 4, or in alternative form and construction as represented by Figures 5 and 9. As best shown in Figures 3 and 4, a self-cleaning screen operable to accomplish the purposes of the invention is constituted as an assembly of like rings 31 concentrically arranged in spaced superposition through the agency of spacer blocks 32 and clamped between an upper header 33 and a lower header 34 by means of bolts 35 engaged through registered ears 36 angularly spaced about and projecting radially from said rings and headers. The assembly of rings 31 and headers 33 and 34 is a hollow cylinder regularly and transversely slotted by the spaces between adjacent rings 31 occasioned by the spacer blocks 32 and is connected by means of the header 34 to and in coaxial relation with the intake end of the line 24 to upstand interiorly of the well 11 below the liquid level obtaining therewithin. The lower header 34 is formed with a central throat adapted to register with the intake end of the line 24 and a spider 37 partially obstructing said throat supports a step bearing 38 coaxial with said throat and the ring and header assembly. The upper header 33 is formed with a bearing 39 therethrough which aligns axially of the ring and header assembly with the step bearing 38, and a shaft 40 is rotatably engaged through the bearing 39 and traverses the ring and header assembly to rotatable engagement of its lower end within the step bearing 38; the said shaft 40 projecting upwardly beyond the header 33 in fixed engagement adjacent its upper end and above the liquid level normally obtaining within the well 11 with an arm 41 fixedly instanding from and radially of the well 11 for rotation therewith. Thus, the assembly of rings 31 and headers 33 and 34 is fixed and held against rotation interiorly of the well by virtue of its connection with the fixed outflow line 24 and the shaft 40 is held by and for rotation with the well 11 in its axially-traversing relation through said assembly, so that generally-arcuate cam fingers 42 fixed in spaced succession to said shaft between the headers 33 and 34 in individual registration with the spaces between adjacent rings 31 are conditioned to rotate with said shaft relative to the associated rings and to repetitiously clear the spaces between the latter. As is clearly shown in Figure 4, each of the fingers 42 is constituted as a web portion non-rotatably engageable with the shaft 40 and an arcuate marginal portion eccentric with respect to the axis of rotation and conformed to constitute a cam 43 wherof the end leading in the direction of rotation registers substantially with the inner margin of the associated ring 31 and the end trailing in the direction of rotation overlaps outwardly beyond the outer margin of the associated ring 31, whereby, as the fingers 42 are rotated between and in clearing relation with adjacent rings 31, the cam margins 43 of said fingers progressively urge matter encountered thereby outwardly from between the rings and exteriorly

away therefrom with a consequent clearing action on the screen assembly effective to maintain an adequate path for the inflow of solution therethrough and to the intake end of the line 24. Inhibitive of material entrance to the ring assembly through the upper header 33, to prevent collection of infed material on said upper header, and to divert infed material to the well space exteriorly about the ring and header assembly, a frusto-conical shield 44 is fixed at its major base area to the header 33 and converges upwardly through the interior liquid level within the well 11 to a lesser upper end spacedly about the shaft 40. Promotive of positive material circulation through the upper portion of the well 11 and past the intake screen defined by the ring and header assembly, a spiral flight 45 is fixed interiorly of the well 11 in an inclination such as to induce travel of material downwardly through the well as an incident of well rotation and in a uniform projection inwardly and radially of the well such as to leave clearance adequate for free circulation of liquid and material between inner margins of said flight and the exterior of the screen assembly just described.

The alternative, functionally-analogous, self-cleaning, intake screen arrangement represented in Figure 9 is constituted as a cylindrical, open-bottom hood 46 of a size to be received within the spiral flight 45 of the well 11 with adequate clearance for circulation therebetween, which hood is formed with a conical extension 47 rising from its upper end to terminate in a capped air vent 48 of usual construction. The hood 46 is telescoped over and secured to the intake portion of the line 24 to dispose the intake end of said line within the upward, conical extension of said hood and to dispose the upper end of the vent 48 above the normal liquid level obtaining within the well 11, whereby to provide for circulation of solution through the open lower end of the hood 46 and upwardly therewithin to the intake end of the line 24. The hood 46 and its extension 47 are so proportioned with respect to the well 11 and outflow line 24 as to provide, when said hood and extension are associated with the outflow line in a manner to dispose the intake end of said line well within the convergent zone established by said extension, that uprise of solution through the open lower end of said hood and through said hood and its extension to the intake end of said line 24 will be at a rate substantially less than the rate of material descent through the liquid charge and past said hood, thereby to obviate any tendency of the liquid uprising within the hood to entrain material infed to the well. In the leaching of sugar beet material, it has been determined that such material settles through a water body at a rate from which the rate of solution uprise within a hood 46 and extension 47 assembly properly proportioned and correlated with the outflow line 24 may be differentiated to such degree as substantially inhibits any entrainment of material with the solution uprise to outflow through said line. Automatically operable in reaction to rotation of the well 11, means for the dispersion of any material tending to collect beneath the open lower end of the hood 46 is expediently provided as indicated in Figure 9, and is typified as a spider 49 fixed to and bridging transversely of the well 11 in free rotatable relation with the line 24 just below the open end of the hood 46, and an angularly spaced series of screen finger assemblies 50 supported by said spider. Each of the finger assemblies 50 is constituted as a succession of spacedly parallel, straight tines progressively greater in length from the line 24 and toward the wall of the well 11 disposed to trail at a downward inclination in the direction of well rotation and to spacedly underlie at their trailing ends the leading ends of the tines in the next and relatively trailing assembly. The hood 46 being fixed to the line 24 which is in turn fixed to the tank 10, and the screen finger assemblies 50 being fixed to the well 11 to rotate therewith, it is obvious that rotation of said

well operates to sweep the successive screen finger assemblies about and across the open lower end of the fixed hood 46 with dispersive effect upon material tending to collect beneath said hood and with an initial impulse urging the material in the desired direction of further circulation.

Alternative to the foregoing, and as represented in Figure 5, the means for inhibiting entrainment of material with the solution outflow through the line 24 may 10 take the form of a cylindrical screen unit 51, of any desired particular type and construction appropriate to pass solution free from the associated material, coaxially engaged with and to upstand from the intake end of the line 24 to terminate in a conical upper end closure below 15 the liquid level normally obtaining within the well 11 effective to divert infed material to the open areas of the well about the unit 51. Impairment of solution inflow through the screen unit 51 resulting from accumulation of material about and against the intersticed walls thereof may be obviated through the provision of a pulsator of suitable type, such as a flexible diaphragm 52 vibratively reactive to a powered, eccentric drive 53, arranged, as through a mounting of the diaphragm transversely of and in contact with the liquid column confined within the portion of the line 24 coaxially uprising within the tank 10, to cyclically pulsate the column of solution in the outflow line immediately below the screen unit 51 for the generation of impulses acting outwardly through the intersticed walls of the unit with dislodging effect upon the material collected thereagainst. When the pulsator is utilized to clear the intake screen, it is expedient to provide a return bend 24' in the outflow line 24 between the pulsator and the weir trap 25 and to arrange said bend 24' as an inverted U whereof 20 the closed base is above the level of intake at the screen unit 51 and below the overflow level of the weir trap, thus to provide a relatively longer liquid column adjacent and in balancing relation with the relatively shorter liquid column immediately below the screen unit which 25 operates to concentrate pulsator effects in and through the shorter column and to substantially eliminate pulsator reactions at the weir trap. A bleeder valve, or vent, 54 in the closed end and at the maximum elevation of the return bend 24' provides means to relieve 30 airlock within and to assure full liquid charge of the solution outflow system just described.

While the spiral flight 45 in the upper portion of the well 11 at an inclination to urge material downwardly of the well as the latter is rotated may be continued 35 to the lower end of the well, or may be interrupted just below the self-cleaning screen comprised from the rings 31 and headers 33 and 34 to permit free settling of the material through the lower portion of the well under the influence of gravity, a feature of the invention productive 40 of circulations facilitating enhanced leaching of the material is the provision of a spiral flight 55, similar to the flight 45, fixed interiorly to and rotatable with the well 11 in an inclination opposite to that of the flight 45 effective to elevate material as the well is rotated and as 45 a reversed continuation of said flight 45 from a termination of the latter just below the self-cleaning screen and to the lower end of the well. The convolutions of the flight 55 intrude radially within the well a distance such as to leave a substantial open space between inner margins of said flight and the outlet line 24, through which space the material elevated by the flight 55 is free to descend and circulate in the manner represented by the arrows in Figure 1, and elongated flat vanes 56 are fixed in angularly-spaced relation to and longitudinally of the line 24 to traverse the length of said line from the lower end of the well 11 and to the base of the self-cleaning screen in such projection radially of the associated line as to freely clear the inner margins of the flight 55; said vanes 56 functioning as the well 11 with its flight 55 is rotated to minimize rotational circulation of the

material and liquid within the lower portion of the well and to stimulate and enhance the desired circulation and agitation of the material descending through the well.

Where, as represented by Figure 9, the elevating spiral flight 55 and fixed vanes 56 are utilized in an organization equipped with the hood 46 controlling outflow of solution through the line 24, upper ends of said vanes spacedly and radially underlying the open lower end of the hood 46 in clearing relation with the rotatable spiral finger assemblies 50 may be expanded radially of the well 11, as at 56'; and the lower ends of the vanes in such organization may be extended radially into adjacency with the lower end of the well 11 as lobes 56" terminating the vanes 56 and susceptible of attachment to areas of the trough wherewith they are in contact. With the lobes 56" present in partially-obstructing relation with the annular trough 29, the blades 30, heretofore described, are necessarily modified in shape to clear the ends of said lobes as said blades rotate with the well 11, or, alternatively, said blades may be discarded in favor of a tongue 57, represented by broken lines in Figure 9, projecting from and extending the lower end of the spiral flight 17 in conformable, clearing relation with the ends of said lobes and the arcuate portion of the trough 29 unobstructed by the lobes; said tongue functioning in an obvious manner to lift and agitate material received within the trough and to recirculate such material as an incident of well rotation.

While the spiral flights 45 and 55 have been hereinabove described and are shown in certain views of the drawings as fixed to the interior wall of the well 11 in a predetermined direction and degree of pitch or inclination, it is within the contemplation of the invention that said flights may be arranged for selective variation of both direction and degree of pitch in a manner accommodating selective adjustment thereof during operation of the apparatus; one practical organization of means effective for such purpose being typified in Figures 5, 6, 7 and 8. Adapting the spiral flights 45 and 55 for selective adjustment of direction and degree of pitch, said flights may expediently be constructed as a succession of separate, arcuate segments 58 of any desired angular extent within a maximum of one hundred and eighty degrees, and each of said segments is fixed at the midpoint of its convex margin to a stub shaft 59 which projects radially from and in the plane of the associated segment to engagement at its free end in a bearing 60 radially of and opening inwardly through the inner wall of the well 11, whereby to mount the segment within said well, expediently adjacent and in clearing relation with the inner wall thereof, and for rotation about an axis radially of the well. The bearings 60 are so distributed circumferentially and axially of the well 11 as to position the segments 58 thereby supported in a desired and practical relationship and operative correlation with the screen and vane assembly centrally of the well; it being expedient to arrange said segments for coaction as spiral flights substantially continuous in either direction of segment inclination. Adjustment of the segments 58 to, and retention of said segments in, a desired direction and degree of inclination is the function of an endless chain 61, or equivalent flexible connection, engaged about a sprocket 62 fixed to the stub shaft 59 of a given segment 58 in the space between the latter and the adjacent wall of the well 11 and extended upwardly along said inner wall of the well to engagement about a second sprocket 63 fixed to the inner end of a stub shaft 64 journalled in and through the wall of said well above the annular flange 13 supporting said well from and in rotatable relation with the tank 10. Externally of the well 11, each shaft 64 fixedly engages with an actuating arm 65 whereby said shaft, and consequently the chain 61, sprockets 62 and 63, and associated shaft 59 and segment 58, may be adjusted to reflect angular displacement of the shaft 64 as corresponding angular dis-

placement of the associated shaft 59 and segment 58, and graduations 66 may be provided on the exterior surface of the well for coaction with one end of the arm 65 in any expedient manner to visually register and, if desired, to yieldably retain the adjusted position of the elements reactive to said arm. With a plurality of segments 58 coacting to constitute a spiral flight in excess of one convolution, the segments of the successive convolutions are conveniently registered longitudinally of the well in interconnection of their successive, so-aligned shafts 59 by means of endless chains 67 in engagement over and operatively between sprockets 68 fixed to said shafts, whereby angular adjustment of the uppermost shaft and segment unit deriving from manipulation of the actuating arm 65 is transmitted to and with corresponding adjustment of the successive lower segments of the flight. In a construction characterized by the chains 61 and associated sprockets within the upper portion of the well 11 above the normal liquid level therein, it is practical to deliver the infed material to said well through a hopper chute, or operatively equivalent facility, having a fixed depending skirt intersecting the normal liquid level of the well through which material may pass to the liquid charge of the apparatus without entanglement in the chain and sprocket assemblies adjacent the inner wall of the well, such arrangement being typified by the hopper chute 21 of Figure 5.

As should be manifest, the various novel features shown in one or another of the several views of the drawings may be separately utilized or variously combined in particular practical installations as may be deemed most practical and expedient. Any of the forms of the intake screen herein disclosed may be utilized with either fixed or adjustable spiral flights on the well interior, with or without the pulsator adjunct, and with or without the annular trough 29 in operative association with the blades 30 or lobe and tongue arrangement 56", 57. Each of the features hereinabove emphasized contributes to enhanced efficiency of sugar extraction from sugar beet material treated through the apparatus wherewith the feature is utilized, and all of said features in operative combination contribute to an efficiency of extraction and a facility of precise operative regulation of major practical and economic importance.

Since changes, variations, and modification in the form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. In sugar diffusing apparatus having a tank adapted to contain liquid, an open-ended, tubular well rotatable about its vertically-disposed axis in a spacing of its lower end above the tank floor and an upward extension beyond the tank, means for the infed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising a tubular, circularly-slotted screen assembly fixed coaxially to, about, and rising above the intake end of said line, a conical upper end closure on said screen assembly intersecting the liquid level plane de-

terminated by said trap, a shaft coaxially journaled in and rotatably traversing the length of said screen assembly in upward projection through said upper end closure, an arm connecting the upper end of said shaft and said well for simultaneous rotation, fingers fixed to said shaft in rotatable engagement within the circular slots of the screen assembly, and eccentric outer margins on said fingers adapted to project at their ends trailing in the direction of rotation radially beyond the screen assembly.

2. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising a tubular, circularly-slotted screen assembly fixed coaxially to, about, and rising above the intake end of said line, a conical upper end closure on said screen assembly intersecting the liquid level plane determined by said trap, a shaft coaxially journaled in and rotatably traversing the length of said screen assembly in upward projection through said upper end closure, an arm connecting the upper end of said shaft and said well for simultaneous rotation, fingers fixed to said shaft in rotatable engagement within the circular slots of the screen assembly, eccentric outer margins on said fingers adapted to project at their ends trailing in the direction of rotation radially beyond the screen assembly, and a spiral fixed flight interiorly about and rotatable for depressing effect with said well marginally spaced outwardly from and substantially coextensive in length with said screen assembly.

3. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising a screen assembly fixed coaxially to, about, and rising above the intake end of said line, a conical upper end closure on said screen assembly intersecting the liquid level plane determined by said trap, a pulsator including a vibratory element operatively associated with said line below the intake end thereof with said element exposed interiorly of the line to altitudinally vibrate the contents of that portion of the line immediately subjacent the screen assembly, and a spiral flight fixed interiorly about and rotatable for depressing effect with said well marginally spaced outwardly from and substantially coextensive in length with said screen assembly.

stantially coextensive in length with said screen assembly.

4. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising a screen assembly fixed coaxially to, about, and rising above the intake end of said line, a conical upper end closure on said screen assembly intersecting the liquid level plane determined by said trap, a pulsator including a vibratory element operatively associated with said line below the intake end thereof with said element exposed interiorly of the line to altitudinally vibrate the contents of that portion of the line immediately subjacent the screen assembly, and a return bend in said line between said pulsator and trap rising to a height above the intake end of the line, whereby to provide an outflow column in balancing, vibration-damping relation with the outflow column immediately subjacent the screen assembly.

5. In sugar diffusing apparatus having a tank adapted to contain liquid, an open-ended tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising a screen assembly fixed coaxially to, about, and rising above the intake end of said line, a conical upper end closure on said screen assembly intersecting the liquid level plane determined by said trap, a pulsator including a vibratory element operatively associated with said line below the intake end thereof with said element exposed interiorly of the line to altitudinally vibrate the contents of that portion of the line immediately subjacent the screen assembly, and a return bend in said line between said pulsator and trap rising to a height above the intake end of the line, whereby to provide an outflow column in balancing, vibration-damping relation with the outflow column immediately subjacent the screen assembly, and a spiral flight fixed interiorly about and rotatable for depressing effect with said well marginally spaced outwardly from and substantially coextensive in length with said screen assembly.

6. In sugar diffusing apparatus having a tank adapted to contain liquid, an open-ended tubular well rotatable about its vertically-disposed axis in a spacing of its lower end above the tank floor and an upward extension beyond the tank, means for the infeed of sugar-bearing material

through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising an open-bottom hood formed with an upper end closure fixedly and coaxially associated with said outflow line to shroud the intake end thereof, and a vent from said upper end closure intersecting and opening above the liquid level plane determined by said trap, whereby to establish a rate of solution uprise through said hood to outflow through the intake end of said line less than the rate at which infed material settles through the liquid charge within the well.

7. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising an open-bottom hood formed with an upper end closure and a vent upstanding from the latter fixedly and coaxially associated with said outflow line to shroud the intake end thereof and to dispose said vent through and to open above the liquid level plane determined by said trap, whereby to establish a rate of solution uprise through said hood to outflow through the intake end of said line less than the rate at which infed material settles through the liquid charge within the well, and a series of like assemblies of spaced, parallel fingers fixedly supported by and for rotation with said well disposed in overlapped, trailing succession to sweep over the open lower end area of said hood as an incident of well rotation.

8. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising an open-bottom hood formed with an upper

end closure and a vent upstanding from the latter fixedly and coaxially associated with said outflow line to shroud the intake end thereof and to dispose said vent through and to open above the liquid level plane determined by said trap, whereby to establish a rate of solution uprise through said hood and to outflow through the intake end of said line less than the rate at which infed material settles through the liquid charge within the well, and a spiral flight fixed interiorly about and rotatable for depressing effect with said well marginally spaced outwardly from and substantially coextensive in length with said hood and the upper end closure thereof.

9. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising an open-bottom hood formed with an upper end closure and a vent upstanding from the latter fixedly and coaxially associated with said outflow line to shroud the intake end thereof and to dispose said vent through and to open above the liquid level plane determined by said trap, whereby to establish a rate of solution uprise through said hood and to outflow through the intake end of said line less than the rate at which infed material settles through the liquid charge within the well, a spiral flight fixed interiorly about and rotatable for depressing effect with said well marginally spaced outwardly from and substantially coextensive in length with said hood and the upper end closure thereof, and a series of like assemblies of spaced, parallel fingers fixedly supported by and for rotation with said well disposed in overlapped, trailing succession to sweep over the open lower end area of said hood as an incident of well rotation.

10. In sugar diffusing apparatus having a tank adapted to contain liquid, an open-ended, tubular well rotatable about its vertically-disposed axis in a spacing of its lower end above the tank floor and upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, a trap in said line exteriorly of the tank determinative of a normal tank liquid level above the intake end of said line, and means for rotating said well, means for inhibiting congestion of infed material about and entrainment of such material with the outflow through the intake end of said line, said latter means comprising an open-bottom hood formed with an upper end closure and a vent upstanding from the latter fixedly and coaxially associated with said outflow line to shroud the intake end thereof and to dispose said vent through and to open above the liquid level plane determined by said trap, whereby to establish a rate of solution uprise through said hood and to outflow through the intake end of said line less than the rate at which infed

material settles through the liquid charge within the well, a spiral flight fixed interiorly about and rotatable for depressing effect with said well marginally spaced outwardly from and substantially coextensive in length with said hood and the upper end closure thereof, and series of like assemblies of spaced parallel fingers fixedly supported by and for rotation with said well disposed at an upward inclination to the vertical in the direction of their rotation and in overlapped, trailing succession to sweep with depressing effect upon material thereby engaged over the open lower end area of said hood as an incident of well rotation.

11. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, means inhibitive of material congestion about and entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge of the well as an incident of well rotation, said latter means comprising a spiral flight fixed interiorly about and rotatable for elevating effect with said well marginally spaced outwardly from and substantially coextensive in length with the outflow line portion between its intake end and the lower end of the well.

12. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, means inhibitive of material congestion about and entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge of the well as an incident of well rotation, said latter means comprising a spiral flight fixed interiorly about and rotatable for elevating effect with said well marginally spaced outwardly from and substantially coextensive in length with the fixed outflow line portion between its intake end and the lower end of the well, and vanes longitudinally of, spaced angularly about, and fixedly projecting radially from said portion of the outflow line subjacent its intake end in marginally-clearing relation with the spiral flight thereabout.

13. In sugar diffusing apparatus having a tank adapted to contain liquid, an open-ended, tubular well rotatable about its vertically-disposed axis in a spacing of its lower end above the tank floor and an upward extension beyond the tank; means for the infeed of sugar-bearing material through the upper end and to the interior of said

well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, means inhibitive of material congestion about and entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge of the well as an incident of well rotation, said latter means comprising a spiral flight fixed interiorly about and rotatable for depressing effect with the length portion of said well above the intake end of the outflow line in a spacing of its inner margins from the means carried by said line, and a second spiral flight fixed interiorly about and rotatable for elevating effect with said well marginally spaced outwardly from and substantially coextensive in length with the outflow line portion between its intake end and the lower end of the well.

14. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, means inhibitive of material congestion about and entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge of the well as an incident of well rotation, said latter means comprising a spiral flight fixed interiorly about and rotatable for elevating effect with the length portion of said well above the intake end of the outflow line in a spacing of its inner margins from the means carried by said line, and a second spiral flight fixed interiorly about and rotatable for elevating effect with said well marginally spaced outwardly from and substantially coextensive in length with the outflow line portion between its intake end and the lower end of the well, and vanes longitudinally of, spaced angularly about, and fixedly projecting radially from said portion of the outflow line in marginally-clearing relation with the spiral flight thereabout.

15. The organization according to claim 14, wherein the spiral flights interiorly of the well are constituted as successions of independent arcuate segments each pivoted at its midlength to the well for adjustment of degree and direction of inclination about an axis radial of the well.

16. The organization according to claim 15, wherein the spiral flights interiorly of the well are constituted as successions of independent arcuate segments each pivoted at its midlength to the well for adjustment of degree and direction of inclination about an axis radial of the well, and separate positioning and control means engage the segments of the upper and lower flights, respectively, for independent, selective adjustment thereof about their mounting axes.

17. In sugar diffusing apparatus having a tank adapted

to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow line fixed through the floor of the tank and centrally of the well with its intake end in an upper zone of the well interior, means inhibitive of material congestion about an entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge adjacent the floor of the tank, said latter means comprising a concave, annular trough arcuately bridging beneath the lower end of the well between the tank and outflow line as a bottom closure for the tank, and blades fixedly depending from and rotatable with said well in marginally-conforming, marginally-clearing relation within the trough concavity.

18. In sugar diffusing apparatus having a tank adapted to contain liquid, an open-ended, tubular well rotatable about its vertically-disposed axis in a spacing of its lower end above the tank floor and an upward extension beyond the tank, means for the infeed of sugar-bearing material through the upper end and to the interior of said well, a continuous spiral flight fixed exteriorly about and rotatable for elevating effect with said well, means for the continuous removal of elevated material from the tank area exterior to the well, means for supply of water to upper regions of the tank area exterior to the well, an outflow

line fixed through the floor of the tank and centrally of the well with its intake end in an upper zone of the well interior, means inhibitive of material congestion about and entrainment through the intake end of said line fixedly associated with and rising above said intake end, a trap in said line exteriorly of the tank determinative of a normal tank liquid level above said last-named means, and means for rotating said well, means promotive of material dispersion and circulation within the liquid charge adjacent the floor of the tank, said latter means comprising a concave, annular trough arcuately bridging beneath the lower end of the well between the tank and fixed outflow line as a bottom closure for the tank, vanes longitudinally of, spaced angularly about, and fixedly projecting radially from the lower portion of said outflow line, radially and longitudinally extended lobes at lower ends of said vanes closing to and across the inner concave arc of said trough in clearing relation with the lower end of the well, and a tongue extension at the lower end of the flight exterior to the well marginally conformed to engage between outer ends of said lobes and the outer concave arc of said trough and in clearing relation therewith as the well is rotated.
